Letters Patent

The schedule referred to in these letters patent, and making part of the same, containing a description in the words of the said James Yale & Philo C. Curtis, themselves of their improvement in the Threshing Machine.

We make a frame of cast iron 9 feet long 4 or 5 inches high the ends are a half circle of 18 inches with the straight edge up, with legs 9 inches in width, running from the round or lower edge 3 inches below the corner in a slanting direction, with feet on the lower end, standing 9 feet 3 inches apart on the floor, with cross girts between the two legs below the half circle, the whole is 95 inch thick with mouldings on the edges projecting outside the machine on the top of the half circle in the center is a box projecting outside the machine to form a bearing of three inches in length, these two ends are fastened together by 2 sills of cast iron 9 ft. long, with flanges at right angles on the ends thru which are bolts and screws to hold them firm, between the ends of the machine about 5 inches above the feet, on a concave of feet long 8 $\frac{1}{2}$ an inch thick on a circle of 18 $\frac{1}{2}$ inches & about 9 inches wide, with flanges rising at right angles at the ends thru which are bolts which hold it to the ends of the machine to correspond with the lower edge of the half circle above described. In this concave are 6 rows of legs, or staves 1 $\frac{1}{2}$ inch high one inch wide at the bottom & 2 inch thick at the bottom & tapering towards the top, set 3 inches apart in the rows in a zig-zag position so as to form 86 spaces 8 inch wide across the bottom of the concave for the spikes or legs in the cylinder to pass thru. — The cylinder is made of sheet iron 1/8 inch thick 9 feet long 4 10 inches in diameter but round to 8 1/2 or 9 1/2 inches, the spikes or legs are made exactly the shape of the 86 spaces of the cylinder, in a straight line, & stand with a large head on the

inside of the cylinder, & the outside is to set down with a wedge when not to form a shoulder on the outside of the cylinder and projecting 1/2 inch from the cylinder, & so placed that 3 spikes will pass through each space in the concave, the heads of the cylinder may be either cast iron, or wood, two which run an arbor of iron, or the 1 1/2 inch diameter with bearings 3 inches long to run in the box before described, on the ends of the machine & secured with caps, bolts & Nut & with one or both ends of the arbor running 1 1/2 inches beyond the box, to receive a pulley to drive the cylinder. A hopper made of
with a cap over the cylinder & dust board in front, having an opening against the cylinder from 6 to 8 inches wide to receive the grain completes the machine. —

What we specifically claim as our invention in the above described machine, is the back iron frame, the sheet iron cylinder & the form of the spiked, or boga, and manner of fastening them into the cylinder &c.
